ESCAPEMENTLIKE CLUTCH

Lawrence E. Wiggs, Worth Township,
Woodford County, Ill.

Application June 20, 1939, Serial No. 280,176

2 Claims. (Cl. 192—45)

This invention relates to an escapementlike clutch, the general object of the invention being to make the device of four primary parts, the driver, the driven member, the escapement and the escapement control, the escapement being accompanied by a rationing of the driving force to the clutching action through a leverage action, by changing the angles of the applied force of the driver and the reactionary force of the driven member to the escapement.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which—

Figure 1 is an elevation of the invention.

Figure 2 is a view with the cover plate removed and parts shown in section.

Figure 3 is a longitudinal sectional view through the device.

Figure 4 is an end view.

Figure 5 is a view of one of the rings or roller retainers.

Figure 6 is a view illustrating the operation of the device.

Figure 7 is a view of one of the rollers.

Figure 8 is a detail sectional view showing how a spring ring engages a ring or retainer and an adjacent part of the housing or casing.

Figure 9 is a perspective view of one of the rings.

In these drawings, the numeral 1 indicates a housing provided with a cover 2 at one end thereof which is fastened to the housing by the screws 3 and the dowel pins 4 and within the housing and its cover are the bushings 5 and 6 and contact screws 7 pass through threaded holes in the cylindrical part of the housing and project in the interior space of the housing. These parts constitute the driver. A shaft 8 extends through the bushing 6 of the cover 2 and has its inner end 8' fitting in the bushing 5. The shaft is provided with an enlarged portion having the rounded projections 9 on its circumference which are separated by rounded recesses. This shaft and its enlargement form the driven member. A plurality of rollers 10 have their pintles 11 held in radiating slots 12 in the retainer rings 13 and each ring has a hole

14 therein for receiving the bent end of a split ring 15, the other bent end of which fits in a hole in either the housing 1 or its cover 2, these rings 13 being of spring metal and these parts, that is, the rollers with their retainers and the spring rings 15 form the escapement and the control would be the adjustment of the contact screws 7.

The housing is provided with a shank 20 for connecting it to a motor or other source of power. The rollers are of hardened and polished steel to prevent excessive wear and the enlarged part of the shaft 8 forms a sprocket. The slots 12 allow the rollers to move inwardly and outwardly in a radial direction from the sprocket and the springs 15 form a firm contact between the rollers and contact screws.

To illustrate the action, assume that power is applied to the driver causing it to rotate in direction of arrow at A (Figure 6) and that the driven shaft is held so that it cannot turn, and that the contact screw 7 be adjusted so that its line of force in relation to roller is B. The counter force of the driven shaft is C. The resultant force is D which forces roller outward and forward and as the escapement unit is free to turn about shaft and inside of housing it has an oscillating movement as the rollers pass around the sprocket projections.

Now if the contact screw be adjusted outward to where its line of force in relation to roller is E which is 180° to counter force of the driven shaft there can be no escapement.

The ratio of the clutching action varies from zero at F to a dead lock at E.

The device can be used in various ways and with different mechanisms. For instance, a handle could be connected with the housing and the driven shaft have a part attached thereto to fit a nut or screw head and this would produce a ratchet type wrench that could be used for tightening bolts or nuts to a given torque. A sprocket projection could be added to the shaft without increasing the number of rollers and thus cause each roller to oscillate independent of the others to provide a more uniform clutching action. Also, means could be provided for adjusting the contact screws 7 simultaneously which would be desirable in the application of the invention to such mechanisms as an automobile driving clutch or brake.

It is thought from the foregoing description that the advantages and novel features of the invention will be readily apparent.

It is to be understood that changes may be made in the construction and in the combination and arrangement of the several parts provided that such changes fall within the scope of the appended claims.

Having described the invention, what is claimed as new is:

1. A device of the class described comprising a casing, a shaft extending into the casing and having a sprocket on that part within the casing, rollers located in the casing and engaging the sprocket, ring retainers having radiating slots therein receiving end portions of the rollers, spring means for connecting the retainers to the casing and projections carried by the casing and extending into the same for engaging the

rollers, and means for adjusting the projections inwardly and outwardly.

2. A device of the class described comprising a housing having a shank at one end thereof, a shaft extending into the housing through the opposite end, means rotatably supporting the shaft in the housing and said shaft having a sprocket thereon within the housing, rollers engaging the sprocket, ring members carrying the rollers and permitting limited radial movement of the rollers and means for yieldingly connecting the ring members to the interior parts of the housing and adjustable members carried by the housing and having their inner ends rounded and extending between the rollers.

LAWRENCE E. WIGGS.
